Atty.

UNITED STATES PATENT OFFICE.

CHARLES K. PICKLES, OF ST. LOUIS, MISSOURI, ASSIGNOR TO SAMUEL M. DODD, OF SAME PLACE.

STEP-OVER CAR-SEAT.

SPECIFICATION forming part of Letters Patent No. 615,224, dated November 29, 1898.

Application filed December 13, 1897. Serial No. 661,721. (No model.)

To all whom it may concern:

Be it known that I, CHARLES K. PICKLES, a citizen of the United States, residing at St. Louis, in the State of Missouri, have invented 5 certain new and useful Improvements in Step-Over Car-Seats; and I do hereby declare the following to be a full, clear, and exact description of the same, reference being had to the accompanying drawings, forming a part of 10 this specification.

This invention relates more particularly to that class of car-seats in which in a reversal of the seat the seat-back will have a step-over movement above the seat portion, an example 15 of which type of seat is shown in my former application for Letters Patent, Serial No. 655,815, filed October 20, 1897.

The objects of the present improvements are to provide a durable and efficient connecting mechanism for the different parts of 20 the chair or seat, with which the movements of such parts with relation to each other are effected in a positive and ready manner and with which the shifting movement that is im- 25 parted to the seat portion is of an amplified nature that will expose for effective use the full width of the seat from front to back, as will hereinafter more fully appear. I attain such objects by the construction illustrated 30 in the accompanying drawings, in which—

Figure 1 is an end elevation of a car-seat embodying the present invention; Fig. 2, a front elevation of the same with portions in section at line *xx*, Fig. 1; Fig. 3, a detail end 35 elevation illustrating the connection between the upper ends of the supporting-arms of the seat-back.

Similar numerals of reference indicate like parts in the several views.

Referring to the drawings, 1 represents the seat proper, to the respective ends of which are attached the end plates 2 of the present improvement. Each of said plates is provided with two or more supporting lugs or 45 projections 3, a toothed rack 4, preferably of a curved or segmental nature, as shown, and a confining slot or recess 5, preferably of a curved nature and concentric with the toothed rack 4.

The chair-base will usually consist of a pair 50 of end supporting-standards, and in the pres-

ent construction will be formed with end plates 6, each of which is formed with a pair of vertically-elongated guide slots or recesses 7 and a horizontal guide slot or recess 8, that 55 is preferably of a curved or segmental nature, as shown.

The horizontal guide slot or recess 8 receives the supporting-lugs 3 of the seat-plate 2 to support and limit the seat in its shifting 60 movement.

9 is the step-over seat-back, preferably of the straight form shown and finished or upholstered on both sides or surfaces.

10 are the supporting-arms of the seat-back 65 9, and, as in my former application above referred to, such arms may be of a substantially counterpart formation, with their upper ends having pivotal connection with the arms of a cross-head 11, attached to each end of the 70 seat-back 9, as shown, while their lower ends are provided with guide lugs or projections 12 and with sector-shaped ends 13, concentric with the guide studs or projections 12 and preferably of a toothed nature, as shown, and 75 adapted to engage with the correspondingly-formed track or toothed rack 4 on the end plate 2 of the seat to impart in the construction shown a combined sliding and tilting motion to the seat 1 and in a direction opposite to that in which the seat-back 9 has movement. The amount of such tilting movement of the seat will depend upon the amount of curvature imparted to the horizontal guide slot or recess 8 in the seat-standard, so that by 85 modifying the form of such slot a corresponding change will be made in the movement of the seat 1.

In the present improvements the guide- 90 studs 12 project from opposite sides of the arms 10 and have a dual or twofold engagement, first, with the confining slots or recesses 5 of the seat-plate 2 to hold the toothed sector 13 in engagement with rack 4 during the reversal of the seat-back, and, second, with the vertically-elongated guide-slots 7 of the 95 chair-standard to hold the sector aforesaid from any but a vertical movement in such slots.

To insure an equal and positive movement 100 of the seat 1 at its respective ends, I make use of the following means: 14 is a shaft

mounted in suitable bearings beneath the seat and extending from end to end of the same. 15 are pinions on the respective ends of said shaft that have engagement with 5 toothed racks 16 on the respective end plates 6 of the seat-standard and which racks will be arranged concentric with the guide-slots 8 in said plates 6.

To insure a like equal and positive movement of the upper ends of the back-supporting arms 10, the construction illustrated in Fig. 3 will be employed. 18 are sector formations on the respective upper ends of the back-supporting arms 10 and which mesh with the 15 teeth of a centrally-arranged pinion 19, arranged upon a shaft 20, that extends longitudinally through the seat-back, and at its other end is provided with a similar pinion to engage counterpart sector formations on 20 the opposite set of seat-supporting arms.

Having thus fully described my said invention, what I claim as new, and desire to secure by Letters Patent, is—

1. In a car-seat, the combination of a seat-standard provided with one or more vertically-arranged confining slots or recesses, means upon the standard for supporting the seat portion in its shifting movements, a shifting seat portion provided with a toothed rack, and 25 a confining slot or recess, a seat-back, means for supporting said back comprising one or more arms having confining-studs engaging the confining-slots in the standard and in the seat portion and provided with toothed sector-shaped ends that engage the toothed rack of said seat portion, substantially as set forth. 30

2. In a car-seat, the combination of a seat-standard provided with one or more vertically-arranged confining slots or recesses, means 40 upon the standard for supporting the seat portion in its shifting movement, a shifting seat portion provided with a segmental toothed rack and a segmental confining slot or recess concentric therewith, a seat-back, 45 means for supporting said back comprising one or more arms having confining-studs engaging the confining-slots in the standard and in the seat portion, and provided with toothed sector-shaped ends that engage the toothed 50 racks of said seat portion, substantially as set forth.

3. In a car-seat, the combination of a seat-standard provided with one or more vertically-arranged confining slots or recesses and a horizontal supporting slot or recess, a shifting 55 seat portion provided with a toothed track, a confining slot or recess, and lugs to engage in the supporting-slot of the standard to guide and support the seat portion in its movement, 60 a seat-back, means for supporting said back comprising one or more arms having confining-studs engaging in the confining-slots in the standard and in the seat portion and provided with toothed sector-shaped ends that 65 engage the toothed rack of said seat portion, substantially as set forth.

4. In a car-seat, the combination of a seat-

standard provided with one or more vertically-arranged confining slots or recesses and a segmental supporting slot or recess, a shifting seat portion provided with a segmental toothed rack, a segmental confining slot or recess and lugs to engage in the supporting-slot of the standard to guide and support the seat portion in its movement, a seat-back, 70 means for supporting said back comprising one or more arms having confining-studs engaging in the confining-slots in the standard and in the seat portion and provided with toothed sector-shaped ends that engage the toothed rack of said seat portion, substantially as set forth. 75

5. In a step-over car-seat, the combination of a seat-standard provided with a pair of vertically-arranged confining slots or recesses, 85 means upon the standard for supporting the seat portion in its shifting movement, a shifting seat portion provided with a toothed rack and a confining slot or recess, a step-over back, and means for supporting said back 90 comprising a pair of arms having confining-studs engaging the confining-slots in the standard and in the seat portion and provided with toothed sector-shaped ends that engage the toothed rack of said seat portion, 95 substantially as set forth.

6. In a step-over car-seat, the combination of a seat-standard provided with a pair of vertically-arranged confining slots or recesses, means upon the standard for supporting the 100 seat portion in its shifting movement, a shifting seat portion provided with a segmental toothed rack and a segmental confining slot or recess concentric therewith, a step-over seat-back, and means for supporting said 105 back comprising a pair of arms having confining-studs engaging the confining-slots in the standard and in the seat portion and provided with toothed sector-shaped ends that engage the toothed rack of said seat portion, 110 substantially as set forth.

7. In a step-over car-seat, the combination of a seat-standard provided with a pair of vertically-arranged confining slots or recesses and a horizontal supporting slot or recess, a 115 shifting seat portion provided with a toothed rack, a confining slot or recess and lugs to engage in the supporting-slot of the standard to guide and support the seat portion in its movement, a step-over back, and means for supporting said back, comprising a pair of arms having confining-studs engaging the confining-slots in the standard and in the seat portion and provided with toothed sector-shaped ends that engage the toothed rack of 120 said seat portion, substantially as set forth.

8. In a step-over car-seat, the combination of a seat-standard provided with a pair of vertically-arranged confining slots or recesses and a segmental supporting slot or recess, a 130 shifting seat portion provided with a segmental toothed rack, a segmental confining slot or recess and lugs to engage in the supporting-slot of the standard to guide and support

the seat portion in its movement, a step-over back, and means for supporting said back comprising a pair of arms having confining studs engaging the confining-slots in the standard and in the seat portion and provided with toothed sector-shaped ends that engage the toothed rack of said seat portion, substantially as set forth.

9. In a step-over car-seat, the combination of a seat-standard, provided with a horizontal supporting-slot and means for confining the back-supporting arms against horizontal movement, a shifting seat portion provided with a toothed track and projecting lugs to engage in the supporting-slot of the standard, to guide and support the seat portion in its movement, a seat-back, means for supporting said back comprising one or more arms having toothed sector-shaped ends that engage the rack on the seat portion, and means for confining the same to their engagement, substantially as set forth.

10. In a step-over car-seat, the combination of a seat-standard provided with a horizontal supporting-slot of a curved formation, means for confining the back-supporting arms

against horizontal movement, a shifting seat portion provided with a segmental toothed rack, and projecting lugs to engage in the supporting-slot of the standard to guide and support the seat portion in its shifting movement, a seat-back, means for supporting the back comprising one or more arms having toothed sector-shaped ends that engage the rack on the seat portion, and means for confining the same in their engagement, substantially as set forth.

11. In a step-over car-seat, the combination of the pairs of seat-back arms, the upper ends of which are provided with toothed sector-shaped parts, a seat-back, a shaft journaled in said seat-back and extending lengthwise the same, and gear-wheels on the ends of said shaft engaging the sector-shaped ends of the series of back-supporting arms, substantially as set forth.

In testimony whereof witness my hand this 11th day of December, 1897.

CHARLES K. PICKLES.

In presence of—

ROBERT BURNS,
G. A. PENNINGTON.
